B. P. JOYCE

SLIDE FOR GUNS

Filed Dec. 3, 1924

INVENTOR
Bryan P. Joyce
BY
W. H. Roach
ATTORNEY

UNITED STATES PATENT OFFICE.

BRYAN P. JOYCE, OF DAVENPORT, IOWA, ASSIGNOR TO THOMAS A. CONLON, OF SILVER SPRING, MARYLAND.

SLIDE FOR GUNS.

Application filed December 3, 1924. Serial No. 753,602.

(GRANTED UNDER THE ACT OF MARCH 3, 1883; 22 STAT. L. 625.)

To all whom it may concern:

Be it known that I, BRYAN P. JOYCE, a citizen of the United States, and a resident of Davenport, county of Scott, and State of Iowa, have invented an Improvement in Slides for Guns, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The subject of this invention is a slide for guns.

When guns provided with slides of relatively great length move on their cradles in recoil, the unequal expansion and contraction of the slides due to the lack of uniformity in the physical properties of different portions thereof results in binding action, deflection of the piece and undue strain on the training mechanism with the consequent necessity of more frequent resighting as firing progresses.

The principal object of the present invention is to avoid binding and warping effect of a continuous slide by breaking its continuity to form a large number of relatively interrupted elements on which are mounted a continuous liner of a thickness insufficient to cause distortion of the gun.

To these and other ends, my invention consists in the construction, arrangement, and combination of elements, described herein-after and pointed out in the claims forming a part of this specification.

A practical embodiment of my invention is illustrated in the accompanying drawings, wherein:

Fig. 1 is a view in right side elevation of a gun constructed in accordance with the invention;

45 Fig. 2 is an enlarged sectional view on the line 2—2 of Fig. 1; and

Fig. 3 is an enlarged sectional view on the line 3—3 of Fig. 1.

Referring to the drawings by numerals of reference:

In carrying out the invention there is shown at 5 the usual barrel surrounded through a portion of its length by a jacket 6.

Formed on the under side of the jacket and extending the entire length thereof are disposed flange members 7, which form slides for the gun as it moves on its cradle in recoil and counterrecoil. The continuity of the flange members is interrupted by a plurality of regularly spaced slots 8 for the purpose of dissipating the heat from the jacket to decrease the amount and the inequality therein of the expansion and contraction of the metal depending on the variation in the rapidity of firing the gun.

The foot portions of the flange members 7 are covered by a continuous liner 9 of bronze or other suitable material to constitute a readily removable bearing surface. These liners are of insufficient thickness to cause distortion of the gun.

It will be noted that the foot of the right hand flange member 7 is formed with a heel portion 10 to constitute a support for securing a retracting rack 11 as specifically covered in Patent No. 1,424,105, issued to me July 25, 1922.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. The combination of a barrel, a jacket therefor, flange members formed on and extending the entire length of the jacket to constitute slides for the gun, said members provided with a plurality of spaced slots, a relatively thin continuous liner for covering the foot portion of each of the flange members, one of said members formed with a heel portion, and a retracting rack secured to said portion.

2. A gun barrel, flange members formed on and extending longitudinally thereof to constitute slides for the gun, said flange members provided with a plurality of spaced slots and a relatively thin continuous liner for covering the foot portions of the members.
3. A gun barrel, flange members formed on and extending longitudinally thereof to constitute slides for the gun, said flange members provided with a plurality of spaced slots and a relatively thin liner for covering the foot portions of the members.
4. A gun barrel, flange members formed on and extending longitudinally thereof to constitute slides for the gun, said flange members provided with a plurality of spaced slots, and a liner for covering the foot portions of the members.
5. A gun barrel, flange members formed on and extending longitudinally thereof to constitute slides for the gun, said flange members provided with a plurality of spaced slots.

BRYAN P. JOYCE.
